(57) **CLAIM**

I claim the ornamental design for a hole punch, as shown and described.

DESCRIPTION

FIG. 1 is a front perspective view of a first embodiment of a hole punch, showing our new design;

FIG. 2 is a rear perspective view thereof;

FIG. 3 is a right end elevational view thereof;

FIG. 4 is a left end elevational view thereof;

FIG. 5 is a front elevational view thereof;

FIG. 6 is a front perspective view of a second embodiment of a hole punch;

FIG. 7 is a rear perspective view thereof;

FIG. 8 is a right end elevational view thereof;

FIG. 9 is a left end elevational view thereof;

FIG. 10 is a front elevational view thereof;

FIG. 11 is a front perspective view of a third embodiment of a hole punch;

FIG. 12 is a rear perspective view thereof;

FIG. 13 is a right end elevational view thereof;

FIG. 14 is a left end elevational view thereof;

FIG. 15 is a front elevational view thereof;

FIG. 16 is a front perspective view of a fourth embodiment of a hole punch;

FIG. 17 is a rear perspective view thereof;

FIG. 18 is a right end elevational view thereof;

FIG. 19 is a left end elevation view thereof;

FIG. 20 is a front elevational view thereof;

FIG. 21 is a front perspective view of a fifth embodiment of a hole punch;

FIG. 22 is a rear perspective view thereof;

FIG. 23 is a right end elevational view thereof;

FIG. 24 is a left end elevational view thereof; and,

FIG. 25 is a front elevational view thereof.

The broken lines showing the top inside surface in FIGS. 5, 10, 15, 20 and 25 are included for the purpose of showing portions of the hole punch that form no part of the claimed design.
